UNITED STATES PATENT OFFICE.

HYMAN COHEN, OF BROOKLYN, NEW YORK.

AUTOMOBILE-HOOD.

1,073,398.

Specification of Letters Patent. Patented Sept. 16, 1913.

Application filed February 4, 1911. Serial No. 606,476.

To all whom it may concern:

Be it known that I, HYMAN COHEN, a subject of the Emperor of Russia, and residing at Brooklyn, in the county of Kings and 5 State of New York, have invented certain new and useful Improvements in Automobile-Hoods, of which the following is a specification, such as will enable those skilled in the art to which it appertains to make 10 and use the same.

This invention relates to hoods for the tops of automobiles when not in use, and the object thereof is to provide such a hood which is neat, compact, and readily placed 15 in position or removed therefrom.

A further object is to provide such a hood, in the shape of a box-like casing, the top, bottom, and back of which are made of strips of material, preferably water-proof, 20 in permanent connection, and the ends of which are enabled to be opened for the entire length thereof, whereby the top and bottom are each freely movable upon the back strip.

A further object is to provide means for 25 maintaining the hood in position and for covering the back cushion of the seat of the automobile in such manner as to be quickly removed therefrom.

A further object is to provide a permanent receptacle or pocket in the bottom of the hood for the reception of the leather or fabric of the automobile top, said receptacle being formed by means of a V-shaped incision in the free edge thereof and the edges 30 thereof being brought together and stitched, this method serving also to approximately conform the inner edge of the bottom of the hood to the configuration of the seat back; and a still further object is to provide such 35 a hood which is very simple in construction and in use, which permits of folding into a compact form when not in use, which dispenses with the necessity for elastic or other adjusting means in order to present a neat 40 appearance, and which is comparatively inexpensive.

My invention is fully described in the following specification, of which the accompanying drawings form a part, in which the 45 separate parts are designated by the same reference characters in each of the views, and in which:—

Figure 1 is a side elevation of my hood in position for use, the flaps thereof being 50 raised to clearly show the construction and method of securing in position; Fig. 2 is a

perspective view of my hood in position and showing the apron for protecting the back cushion of the seat; Fig. 3 is a bottom plan view of my hood removed from the automobile; Fig. 4 is a section taken through my hood on the line 4—4 of Fig. 2; and Fig. 5 is a fragmentary view of one step in the operation of forming a detail of the construction.

In the drawings forming a part of this application I have shown a portion of an automobile *a* provided with a collapsible top *a*², of the ordinary or any desired type, and which is adapted to be covered by my hood when not in a protecting position, said automobile being provided with a back cushion *a*³ for the seat thereof, and said hood being provided with the usual bows *a*⁴.

My improved hood comprises a top member *b* provided with an apron *b*² in turn provided with straps *b*³, or the equivalent, said top member being connected with a narrow back strip *c* of the same length as the member *b* and which is in turn connected with a bottom member *d* of approximately the same 75 size and shape as the top member *b*, exclusive of the apron *b*², said bottom member *d* having one or more V-shaped incisions *d*² formed therein in the manufacture of my 80 hood and the edges of which are joined together as shown at *d*³, Fig. 3, this method of construction resulting in the formation of a permanent, slightly sagged, receptacle in the bottom member *d*, and serving also to conform the inner edge of the said bottom member approximately to the rear of the automobile, as clearly indicated in Fig. 3, only one of said incisions being shown, but it will be understood that by the employment 85 of more of the said incisions the conformation of the inner edge of the bottom member will approach more nearly to that of the automobile back and will produce a 90 correspondingly formed and enlarged belly 95 or receptacle therein.

Secured to the ends of the top member *b* are two flaps *e*, one at either end thereof, said flaps being preferably stitched or otherwise secured to the back strip *c*, as shown at 105 *e*², and being provided with an element of a plurality of fastening devices *e*³ along the bottom edge thereof adapted to engage with complementary elements of the fastening devices on the bottom member *d* or on strips 110 *e*⁴ secured thereto, this method of construction permitting the free opening of the hood

all the way to the back member *c* and, because of the downward direction of the overlap of the flaps at the openings, making the hood water-proof.

5 Secured to the bottom member *d*, or to the strips *c*⁴ thereof, are straps *f* provided with suitable buckles or the like, one at each end of the hood, these straps being adapted to be passed about the bows of the automobile top to hold the bottom member in position, the top member being held in position by means of the straps *b*³ of the apron *b*² being passed beneath the cushion *a*³ and by means of the fasteners thereon adapted 15 to be connected with the bottom member *d*, or the strips *c*⁴ thereof, the said top member being entirely free to be thrown open and backwardly without affecting the position of the remainder of the hood, thus serving 20 also, if desired, to cover various articles stored thereunder.

In placing my hood in position the hood is slipped over the collapsible top and the straps *f* secured in the positions shown, after 25 which the straps *b*³ are placed under the cushion *a*³ to hold the apron in position and, when the flaps *c*³ are fastened to the bottom member *d*, a very neat, simple, compact, and protecting hood results, the permanent 30 receptacle in the bottom member *d* serving to contain the portions of the leather or fabric covering of the top, which would otherwise hang downwardly, in close confinement and, as will be readily seen, my hood is removed 35 even more rapidly than it is placed in position.

It will be observed that I employ no straps for adjusting the tension of the members of my hood, nor do I employ elastic 40 devices, for this purpose, which frequently require repair or substitution, my hood, when once fitted to an automobile, being permanent in all its features, there being

nothing whatever forming a part thereof which is likely to get out of order to require 45 repair or which is likely to require substitution and, while I have shown a preferred form of embodiment of my present invention, it will be obvious that changes there-over may be made, within the scope of the 50 following claims, without departing from the spirit of my invention or sacrificing its advantages and,

Having fully described my invention, what I claim as new, and desire to secure by 55 Letters Patent, is:—

1. A hood for automobile tops, comprising a top member, a back member permanently secured thereto, a bottom member in permanent connection with said back member and adapted to swing downwardly at its junction therewith, and end flaps permanently secured to said top member and adapted for detachable engagement with said bottom member for the full length of 60 65 said end members.

2. A hood for automobile tops, comprising a top member, a back member in permanent connection therewith, a bottom member in permanent connection with said back 70 member and adapted to swing at its junction with said back member, and end flaps in permanent connection with both said top and back members and means for detachably connecting the end flaps with said bottom member, for the full length of said end 75 flaps.

In testimony that I claim the foregoing as my invention I have signed my name in presence of the subscribing witnesses this 80 2nd day of February 1911.

HYMAN COHEN.
